ABSTRACT OF THE DISCLOSURE

A portable derrick having means provided with the block thereof, which serves to sustain one axially disposed marginal portion of a conventional plaster board building ceiling panel in substantially pivotal relation with the axially disposed underside edge of a pre-framed ceiling joist, thereby said panel may be swung in an upward direction into contiguous depending relation with a plurality of identical spaced joist for nailing thereto.

My invention relates to a portable derrick which serves to facilitate the installation of a cumbersome plaster board panel to the ceiling joists of a building, and more particularly to the block thereof.

My invention resides in a portable derrick having means provided with the block thereof, which serves to sustain one axially disposed marginal portion of a conventional plaster board building ceiling panel in substantially pivotal relation with the axially disposed under-side edge of a pre-framed ceiling joist, thereby said panel may be swung in an upward direction into contiguous depending relation with a plurality of identical spaced joists for nailing thereto.

The main object of my invention is to provide an implement of the aforementioned characteristics which will serve to enable a single journeyman to install a conventional plaster board building panel to the underside edges of a plurality of spaced ceiling joists composed of wood.

Another object of my invention is to provide a derrick which can be sustained in angular relation with both the floor surface and underside edge of a prefabricated ceiling joist.

A further object of my invention is to provide such a device which can be quickly and easily assembled for its intended use, and easily moved from one location to another within either a building or in a suitable vehicle.

A still further object of my invention is to provide such an implement which will be relatively light in weight, durable in construction, for the everlasting use thereof, and which may be relatively economically produced.

Other objects and advantages of my invention will henceforth become readily apparent when evaluated from the following detailed description, and accompanying drawing thereof, and wherein:

FIGURE 1 is a view in vertical section of a preferred embodiment of my invention.

FIGURE 2 is a view in side perspective thereof, and wherein certain sights have been provided in order to reveal inner elements of construction, and further, the view includes a substantial illustration of the use thereof.

FIGURE 3 is an enlarged view in real elevation of FIGURE 2.

Now referring to the details within the several cited views, the numeral 10 indicates in general my invention, and wherein it is shown to comprise the elongated mast 11 of selective length, which is provided with a rectangular cross section, and wherein mast 11 is composed of wood, though it may be constructed of other materials, providing the cost thereof is not prohibitive.

With reference being had to FIGURE 1 therein is shown that mast 11 is provided with an axial bore 12 in

2

the medial lower body portion thereof, which is adapted to slidably complement in telescopic relation therewith a substantial body portion of the jack-screw 13, which is shown to be disposed in threaded relation with the end wall 14 of the cup shaped rectangular casing 15, which is adapted to slidably complement a transverse end body portion of the cited lower body portion of mast 11, for fixed contiguous depending relation therewith, as when anchored thereto by the plurality of opposed screw fasteners 16.

Further, jack screw 13 is integrally provided with the ball member 17 of the pivotal union 18 wherein the socket member 19 thereof is formed in the apex of the inverted cone shaped wall of base plate 20, and serving to facilitate the inward or outward threading of the jack-screw 13 in respect to the mast axial bore 12, there is provided in slidable transverse relation with the lower body portion of jack-screw 13, the handle-bar 21.

Now with additional reference to FIGURE 3 wherein it is shown that the block 22 surmounts both laterally and extensibly the upper-most body portion of mast 11, and wherein derrick block 22 is shown to comprise a substantially open ended housing as provided by the pair of substantially rectangular comated wall plates 23, 24, which bridge the opposite side faces 25, 26, of mast 11 respectively, in fixed relation therewith, as by virtue of the pair of spaced bolt fasteners 27, 27, which are transversely affixed therewith. Further, wall plates 23, 24, are provided with inturned lateral flanges 28, 28, which are disposed in contiguous relation with the transverse side face of mast 11, and in spaced relation relative to each other, thereby providing an axially disposed opening therethrough which superposes mast 11, through which projects a sector portion of a flat rimmed sheave 29, which is journaled upon the shaft afforded by the bolt fastener 30, which is affixed in transverse relation with housing wall plates 23, 24, and wherein sheave 29 is spaced from the end wall face of mast 11.

Sheave 29 serves to track an open ended flexible strap 31 trained medially thereon, and wherein an inner body portion 32 thereof is disposed in overlapping contiguous relation with the backstay 33 which comprises an elongated rectangular plate member 34 adapted to interpose in transverse relation housing wall plates 23, 24, and in inclined relation with mast 11, as when the pair of opposed transversing sleeve members 35, 35, which depend integrally from backstay 33 are slidably secured upon the pair of shafts afforded by the pair of spaced bolt fasteners 36, 36, which are affixed in transverse relation with housing wallplates 23, 24. Thereby strap 31 may be constrained from moving through derrick block 22 in an outward direction, by the pawl 37 which is provided with a sector shaped eccentrically disposed periphery or brake-shoe 38 with one free end portion thereof, wherein the opposite end portion thereof is journaled on the shaft afforded by the bolt fastener 38a which is disposed in affixed transverse relation with housing side-wall plates 23, 24, in a manner whereby the lesser radial extent of brake-shoe 38 will be disposed in contiguous complementary relation with the cited body portion of strap 31 which has been said to overlap backstay 33 as when pawl 37 is manually swung in a counter clockwise direction, thereby the brake-shoe 38 thereof will progressively increase the intensity of a clutching pressure thereon, for the reason that its periphery increases simultaneously in length, and which recited positioning of brake shoe 38 in respect to strap 31 is automatically retained by virtue of the pull spring 39, which interposes in fixed relation both the annular grooved body portion 40 of the stub-shaft 41 which is fixedly secured in inwardly disposed lateral relation with block housing side-wall 23, and with the perforated body portion 42 of the depending tri-

angular shaped member 43 which is integrally provided with the journaled body portion of pawl 37. It now being axiomatic that the brake means as recited will permit strap 31 to move in a downward direction in respect to backstay 33, as when a manually applied pulling action is applied upon the free end portion thereof, for the reason that brake-shoe 38 will be influenced by a frictional action transposed thereon by strap 31 to move accordingly, and to simultaneously release its recited pressure thereon, and for the purpose of providing a means whereby use of the braking means may be selective in use of the invention, then for this reason there is provided a pull cord 44 which hangs freely in secured relation with the eye body portion 45 of eye-bolt fastener 46 which is affixed in depending transverse relation with pawl 37 adjacent brake-shoe 38.

Pull-cord 44 is provided with a substantial knot 47 adjacent the eye body portion 45 of eye-bolt 46, and which knot 47 normally superposes in spaced relation the eye 48 of a keyhole opening provided through a rectangular plate 49 which is adapted to interpose in transverse relation a lower body portion of the block housing side wall plates 23, 24, and wherein plate 49 is secured with the latter in a manner previously described for backstay 33, whereby it is now apparent that when pull-cord 44 is extended through key-hole eye 48 that knot 47 will follow accordingly and pass therethrough, and when pull cord 44 is slidably passed into the communicating key-hole slot 49a and released therein that pull-spring 39 will act to draw knot 47 against the underside face of plate 49, thereby pawl 37 will be simultaneously influenced to move in a clockwise direction, and wherein brake shoe 38 will be spaced from strap 31, of which the outer free end body portion 50 thereof is disposed in looped fixed relation as at 51 with the bail body portion 52 of a depending rectangular shaped hook 53, which normally is disposed in nestled relation with a pair of complementary hooks 54, 54, which extend in lateral integral relation with a pair of elongated rectangular plates 55, 55, respectively of identical shape. Plates 55, 55, are adapted to extend laterally from the opposite side faces 25, 26, of mast 11 respectively, as when clamped thereagainst by the pair of diagonally spaced bolt fasteners 56, 56, which are affixed transversely with plates 55, 55, and in tangible slidable relation with the opposite transversely disposed pair of faces of mast 11, thereby hooks 54, 54, may be simultaneously disposed in adjusted relation with mast 11, and normally, hooks 54, 54, are disposed upon the lower-most body portion of mast 11, the purpose of which will be henceforth described.

Now with reference being had to each respective view in the drawing, there is shown that block 22 carries in transverse recessed weldingly fixed relation therewith the angle iron bar 56 of which the medial body portion thereof is spaced in superposed relation with sheave 29, in a manner wherein the bar leg 57 is disposed at right angles to the top free edges of housing plates 23, 24, and the associated bar leg 58 is disposed at right angles with the plate flanges 28, 28. Further, bar 56 includes a plurality of spaced bayonets 59, 59, 59 of circular cross section which are disposed in upstanding weldingly fixed relation with the inwardly disposed face 60 of bar leg 57, and which serve a henceforth described purpose.

Now with particular reference to FIGURE 2 wherein the use of my invention is illustrated there is shown that mast 11 is disposed in extended interposed fixed relation with the floor surface 61 and the ceiling joist 62 of a building (not shown) in a manner whereby the vertically disposed leg 57 of angle iron bar 56 is disposed in axial relation with an outwardly disposed body portion 63 of the underside axially disposed edge of joist 62, and in contiguous angular relation therewith, as when bayonets 59, 59, 59, have previously been directed by virtue of jackscrew 13 to pierce the recited edge in a complementary angle thereto, and by virtue of the recited pivotal

union 18, then derrick 10 will be enabled to sustain itself in a slightly inclined position. Thereby mast 11 will be enabled to track the movement of the plaster board panel 64 in the direction of the indicating pair of arrows 65, 65, as when the lower axial edge 66, of panel 64 is balanced upon the stirrup bar 67, afforded by the hook 53, which has been recited as being stabilized by the pair of overlapping hooks 54, 54 and wherein the opposite axial edge 68 of the panel will be disposed against a body portion of flexible strap 31 which itself will be influenced to glide upon mast 11 by the inclined position of the panel in respect thereto, as when a manually applied pulling action is applied upon the free end of the strap 31, and by virtue of the purchase afforded by block 22, then the axial panel edge 68 may be sustained in pivotal depending relation with the inwardly disposed axial edge 69 of joist 62, wherein panel 64 will lend itself for a swinging action in the direction of the indicating pair of arrows 70, 70, as applied thereon by the journeyman, as when both grasping the panel edge 66, and simultaneously ascending a step ladder, and when panel edge 66, is disposed in contiguous depending relation with the underside edge 71 of a pre-positioned joist 72, then it being axiomatic that the opposite panel edge 68 will be disposed in complementary axial relation with the opening afforded by the angle iron bar 56 wherein the edge may be recessed therein, wherein the strap 31 will now have a slack body portion provided in depending relation with panel 64, which will enable the journeyman to remove the hook 53 therefrom, and to secure the panel edge 66 to joist 72, as by nailing, and with a similar operation provided with the opposite axial edge 68 of panel 64, then conventionally it will sustain itself in a finished position, and wherein derrick 10 may then be collapsed and relocated for the re-use thereof.

I claim:

1. In a derrick for use in the installation of a plaster board ceiling panel, comprising a base adapted to rest upon the surface of a floor, a jack-screw united in pivotal upstanding relation with the central body portion of said base, a casing having a rectangular shaped body, adapted for threadable relation with said jack-screw, a mast comprising an elongated member adapted for a fixed telescopic connection with said casing, said mast provided with an axial bore within the fixed end portion thereof to accommodate the extent of said jack-screw therein, a handle slidably fixed in transverse relation with a lower body portion of said jack-screw to facilitate the alternate threading of said jack-screw as when extending or retracting said mast in respect to said base, a bracketed hook disposed in slidable adjustable relation with a lower body portion of said mast, and wherein said hook extends laterally from one side face thereof; a derrick block provided with the opposite free end of said mast, comprising a pair of substantially rectangular co-mated plates fixedly secured with the transverse side faces of said mast respectively, said plates adapted to extend laterally from the opposite side face of said mast, and extensibly the end wall thereof, said plates including a pair of spaced inturned flanges disposed in contiguous relation with the first said side face of said mast, a flat rimmed pulley disposed rotatably in interposed relation with said plates, and superposed relation with said mast end wall, said pulley adapted to project a sector body portion thereof through the opening afforded by said flanges, whereby the alternate side-wise movement of said pulley in respect to its shaft is obviated, a flexible elongated open ended strap having a medially disposed body portion thereof trained about a radially disposed sector body portion of said pulley, wherein the free end body portions thereof will be disposed in complementary relation with the said pair of side faces of said mast respectively, a second hook formed of an elongated strap element having a bail member disposed in fixed relation with the outwardly disposed terminal body portion of said strap, and a flat web member constituting herein

a stirrup, said hook adapted to normally rest in interfitting slidable relation with said first mast hook for stabilizing the latter in respect to said mast means for detachably securing said derrick block in transverse relation with an inwardly disposed marginal portion of the underside edge of a pre-framed ceiling joist composed of wood, whereby said derrick may be supported in interposed slightly inclined fixed relation with both said floor and said ceiling joist, and thereby said mast will accommodate an elongated rectangular shaped plaster board building panel thereagainst, through an interposed body portion of said strap, as when the lower longitudinally disposed edge of said panel is positioned in a balanced state within said hook, for support upon said stirrup, thereby said panel may be elevated in slidable relation with said mast into pivotal fixed relation with the outwardly disposed axial portion of said underside edge of said joist, by virtue of said block and tackle, means to fixedly sustain said depending position of said panel in respect to said joist, and means provided with the first said means for supporting a medially disposed marginal portion of said pivoted panel edge against the underside edge of said joist, as when said panel is swung in a counterclockwise direction from said mast towards a second ceiling joist spaced in parallelism with the first said joist by virtue of the fixed extent of said strap in respect to said block.

2. As claimed in claim 1, wherein the detachable securing means for supporting said inclined positioning of said derrick in respect to said floor surface and said joist comprises a plurality of spaced bayonets which are disposed in weldingly fixed transverse extensible relation with the outer face of one flange of an elongated angle iron bar which is affixed in transverse medial recessed relation with the said housing sidewalls corner edges which superpose said pulley, in a manner whereby the axis of said vertically disposed angle iron flange has its free edge disposed in flush relation with the top free edges of said housing sidewalls, and wherein the associated angle iron flange has its free edge aligned in flush relation with the depending pair of housing sidewall flanges, thereby said bayonets will be aligned in axial relation with said mast, and when directed in slightly inclined relation with the under-side edge of said ceiling joist while simultaneously positioning said mast they may then be forced to pierce said joist, by virtue of said screw-jack when simultaneously extending said mast and said block into the previously described selective positioning thereof in respect to both said floor surface and said underside edge of said joist.

3. As claimed in claim 1, wherein the means for sustaining the upper axially disposed free edge of said plaster board panel in fixed pivotal relation with the underside edge of said joist, as when elevated thereagainst by virtue of said block and tackle comprises a pawl member having an integral eccentrically disposed sector shaped end portion constituting herein a brake-shoe which is adapted to latch upon in frictional transverse relation a body portion of said strap as when disposed in overlapping contiguous relation with a back-up plate constituting herein a stay, which is disposed in interposed fixed transverse relation with said housing side-walls, and wherein said pawl member is adapted for pivotal relation with a bolt fastener which is disposed in affixed transverse relation with said housing side walls and in spaced relation with

said stay, and further, wherein said pawl is resiliently biased to move in a counter clockwise direction by virtue of a pull spring, thereby said brake-shoe will be simultaneously influenced to progressively move the increasing radially disposed extent thereof into locking relation with said interposed body portion of said strap, as when the outwardly disposed body portion thereof in respect to said block is tensioned in a down-ward direction by the weight of said plaster board panel when carried by said stirrup in an elevated position in respect to said mast hook, brake releasing means connected with said pawl member for selectively spacing said brake shoe from said strap, as when said stirrup is to be stabilized by said mast hook by a downwardly directed pulling action manually applied upon the said outwardly disposed body portion of said strap for moving said stirrup in the direction of said mast hook.

4. As claimed in claim 3 wherein the brake releasing means comprises a pull cord depending in fixed relation with said pawl member adjacent said brake-shoe, and wherein said pull cord is provided with an enlarged knot which normally superposes the eye of a keyhole provided in a rectangular shaped plate, which is disposed in interposed transversely fixed relation with said housing side walls, thereby said knot may be passed through said eye by a manually applied pulling action applied upon the free end portion of said pull cord, and when said knot is disposed in bearing relation with the underside face of said keyhole slot as when passed thereunder by virtue of said pull cord, said brake-shoe will be simultaneously influenced to move in a clockwise direction and from said strap.

5. As claimed in claim 1, wherein the means provided with the first said means for supporting a medially disposed marginal portion of said pivoted panel edge as when swung radially in a counter clockwise direction and towards a second joist spaced in parallelism with the first said joist, as from the initial positioning thereof to a second substantially horizontal position, by virtue of the hold thereon by said strap hook, comprises the ledge provided by the substantially horizontally disposed flange of said angle iron bar, and which said flange is spaced from the underside edge of said first joist, thereby said pivoted panel edge may be simultaneously disposed within said recess as when moved from said underside edge of said joist during the previously described swinging action applied upon said panel thereby providing a slack body portion within said strap for accommodating the release of said strap hook from said panel edge for nailing said freely disposed panel edge to the underside edge of said second ceiling joist.
